UNITED STATES PATENT OFFICE.

JAMES T. SHELLEY, OF LOUISVILLE, KENTUCKY.

SLOW-FEEDING SANITARY TUB FOR STOCK.

1,215,725.

Specification of Letters Patent.

Patented Feb. 13, 1917.

Application filed April 24, 1916. Serial No. 93,181.

To all whom it may concern:

Be it known that I, JAMES T. SHELLEY, a citizen of the United States, residing at Louisville, county of Jefferson, and State 5 of Kentucky, have invented certain new and useful Improvements in Slow-Feeding Sanitary Tubs for Stock, of which the following is a specification.

This invention relates to a slow feeding 10 sanitary tub for stock.

Among the objects of my invention are the provision, first, of an improved sanitary feed tub which will deliver the feed to the feeding space at a relatively slow rate; second, 15 a feed tub having an improved construction adapting it to prevent the feed from being splashed or thrown out by the animal, thus preventing waste; third, a feed tub which will be constructed so as to carry 20 out the foregoing objects and also adaptable for quick and easy flushing and cleansing and will be readily portable so that it may be removed from the stall and hung in the open air to keep it sanitary; fourth, 25 improvements adapting the tub to supply the requisite quantity of feed to the animal and yet, prevent the latter from "nosing" out the feed or injuring himself when feeding.

30 My improved sanitary slow feeding tub is preferably of circular form adapting it to be nested in a shipping case so that a number of these tubs may be readily shipped in compact form, and it is adapted to be put 35 up in any part of the stall and readily removed therefrom. Harness snaps may constitute the means for securing the tub in position when resting on any support, adapting it for feeding purposes and by the 40 disconnection thereof the tub may be readily removed for use in another stall or to be cleansed.

A practical embodiment of the invention 45 comprises a circular tub having an annular internal shelf or flange provided with openings, preferably where the flange or shelf joins the inner wall of the tub, and a self-feeding reservoir or hopper for delivering the feed to the interior of the tub, as hereinafter set forth and pointed out in the 50 appended claim, but as I am aware that modifications may be resorted to, the disclosure of the invention is to be considered as illustrative, rather than restrictive, of the 55 scope thereof.

In the accompanying drawings:

Figure 1 is a perspective;

Fig. 2, a plan view;

Fig. 3, a vertical section taken through the feed hopper or reservoir; 60

Fig. 4, an enlarged detail section showing the knob on the lid of the feed hopper; and

Fig. 5, an enlarged detail section of the flange. 65

The body or tub 1 is preferably of circular form and is made of galvanized sheet metal provided with handles 2 by which it may be carried about, hung up to air, or connected to any suitable fastenings, such as 70 harness snaps to hold the feed tub on any suitable support when being used.

Secured to the inside of the wall of the tub 1 at a point preferably a few inches below the upper edge thereof, is a substantially annular shelf or flange 3 which has an angular portion 4 by which it is secured by rivets 5, and also by soldering if desired, to the tub 1. The inner edge of the shelf or flange is formed into a bead 6 which encompasses a wire 7. At suitable intervals, 75 the part 4 and the shelf or flange 3 are provided with notches 8.

The feed hopper or reservoir 9 is provided with an inclined self-feeding bottom 85 10 leading to an outlet 11 which is adapted to deliver the feed onto the feed space or bottom 12 of the tub 1. The reservoir or hopper 9 is provided with a cover 13 hinged at 14 and having any suitable knob or lifting means 15, but preferably a galvanized metallic knob secured by a rivet 16, as shown in Fig. 4.

The feed box or reservoir 9 has its side walls joined to the flange or shelf 3 by 95 angular portions 17 which may be soldered or riveted to the feed box.

Preferably, all of the parts of the device are of galvanized metal so that rusting or corroding of any part thereof will not 100 occur, and enabling all parts to be kept cleanly and sanitary. The animal can only feed by inserting his muzzle through the opening in the shelf or flange 3 and cannot splash or blow out the feed on the feeding 105 space or bottom 12 as the flange or shelf 3 constitutes a dash or baffle which will return the feed to the bottom of the tub if it is blown or forced upwardly. The reservoir or hopper 9 constitutes a gravity or auto- 110

matically feeding device which delivers small quantities of the feed on the bottom of the tub 1, thus preventing too rapid feeding of the animal. The rounded or beaded 5 inner edge 6 of the shelf or flange 3 prevents injury to the muzzle of the animal.

The tub being readily portable, may be moved from place to place, hung up to air or to drain and otherwise conveniently handled. To cleanse the feeding tub, it may 10 be flushed with water which will drain off through the openings 8, rendering cleansing and drying very easy.

Having thus described my invention, what 15 I claim as new and desire to secure by Letters Patent, is:—

A portable feed tub for stock comprising

a body, a flange contained within, and continuously joined at its outer edge to, the body below the upper edge thereof, said 20 flange being provided with openings at intervals in the region of the juncture thereof with the wall of the body, and a feed hopper contained within the body and provided with a closure at its top, a self-feed- 25 ing bottom and a mouth in its inner face adapted to deliver the feed to the central portion of the bottom of the body below the flange, the ends of said flange being joined to the opposite sides of said hopper. 30

In testimony whereof, I hereunto affix my signature.

JAMES T. SHELLEY.
